C. A. NELSON.

FIREARM.

APPLICATION FILED JUNE 19, 1917.

1,246,984.

Patented Nov. 20, 1917.

UNITED STATES PATENT OFFICE.

CHARLES A. NELSON, OF UTICA, NEW YORK, ASSIGNOR TO SAVAGE ARMS CORPORATION,
A CORPORATION OF DELAWARE.

FIREARM.

1,246,984.

Specification of Letters Patent. Patented Nov. 20, 1917.

Application filed June 19, 1917. Serial No. 175,562.

To all whom it may concern:

Be it known that I, CHARLES A. NELSON, a citizen of the United States, residing at Utica, in the county of Oneida and State 5 of New York, have invented certain new and useful Improvements in Firearms, of which the following is a specification.

This invention relates to magazine firearms of the class in which the breech-bolt 10 is movable for opening and closing the breech longitudinally of the barrel, and it has for its object to provide means for removably securing in place the cartridge box or equivalent which shall be simple and durable in construction and adapted reliably to hold such box or equivalent in place 15 and to permit the introduction or removal thereof with facility. A further object is to provide a novel means to adapt the arm 20 for the feeding of the cartridges one by one by hand.

In the accompanying drawing,

Figure 1 is a fragmentary side elevation of a magazine firearm having the part 25 thereof with which my invention is immediately concerned in section, a cartridge box being shown in the magazine cavity or opening;

Fig. 2 is a similar view, showing the 30 adapter in said opening; and,

Figs. 3 and 4 are a side and a rear elevation of the adapter.

a is the barrel having a rearward extension *b* forming the breech-casing, which 35 contains the longitudinally movable breech-bolt, the rearward part *c'* of which is capable of rotation in the breech-casing to lock and unlock the breech-bolt (*d* being the usual handle for rotatably shifting it) and 40 the forward part *c''* of which is held against turning by a depending rib *c'''* which engages in a suitable groove in the breech-casing. The breech-casing has a lateral cartridge-shell delivery opening *e*.

f is the stock to which the barrel is secured 45 by the long screw *g* which, with screws *h*, also secures to the stock the trigger guard *i*.

j, *k* and *l* represent the trigger, striker and firing pin, respectively, of the firing 50 mechanism.

The shell-delivery opening *e* is immediately back of the barrel-breech and in the same transverse section of the gun the breech-casing *b* has an underneath opening 55 *m* and the stock and trigger guard an open-

ing *n*. These openings *m* and *n* form a cavity to receive the cartridge box *o*, adapted to be entered into and removed from said cavity vertically.

The cartridge box *o* contains a spring-pressed platform *p* for elevating the cartridges and on its rearward side has a vertical rib *q* beveled at its upper end and forming at its lower end a shoulder *r*. A metal piece which in the construction shown 60 is the trigger guard at *s* forms a shoulder at the lower rear side of opening *n*. When the box is entered into the cavity, it is pressed back by a spring *t* which, when the box is finally pushed home, causes the latter 65 to spring rearwardly so that the rib *q* snaps into abutting relation to the shoulder *s*. The box may be removed by employing its handle *u* to force it forward, till its rib at *r* clears shoulder *s*, and then downward. 70 Spring *t* is a plate spring having one end clamped between the barrel and stock and held in place by screw *g*, its other end being bent downwardly and curved. According to 75 a well known construction, the breech-bolt is 80 adapted to be blocked against forward movement when it is retracted upon the firing of the last cartridge by engagement of the rib *c'''* on its forward member *c''* with the magazine platform.

To adapt the gun for the firing of cartridges one by one by hand I provide the block *v* conforming generally to the outward shape of the box except that its top face affords a rigid cartridge seat *w* having a longitudinal depression or groove *x* to accommodate the rib *c'''* of the breech-bolt. When this adapter has been fitted to the gun in the same manner as the magazine box and in place thereof the cartridges 90 may be fed by hand into the gun through the shell-delivery opening *e*, the top or seat *w* supporting the cartridge until the breech-bolt is allowed to advance it into the barrel-breech.

Having thus fully described my invention, what I claim as new and desire to secure by Letters Patent is:—

1. In combination, with the fixed breech-including part of a gun, and the breeching and firing mechanism, said part having a magazine-receiving opening and including separate members rigidly secured together, a magazine in said opening, and a plate spring clamped between said members and 105 110

- exerting clamping pressure on the magazine.
2. In combination, the barrel, breeching and firing mechanism, a stock supporting the barrel and having a magazine opening, a magazine in said opening, and a plate spring clamped between the barrel and stock and having one end exerting clamping pressure on the magazine.
3. In combination, with the fixed breech including part of a gun, and the breeching and firing mechanisms, said parts having a magazine-receiving opening, a removable cartridge magazine in said opening, a plate spring secured to said part and having one end bent off and arranged in said opening and exerting clamping pressure on the magazine.
4. The combination, with the fixed breech including part of a gun having a magazine-opening entering the same from below immediately back of the breech, a longitudinally movable breeching structure, and firing means, of means to adapt the gun for the firing of cartridges one by one by hand
- consisting of a rigid cartridge-supporting member removably arranged in said opening and having a cartridge-supporting seat to form the rigid bottom of the space immediately back of the breech in the rearward position of the breeching structure.
5. The combination, with the fixed breech including part of a gun having a magazine-opening entering the same from below immediately back of the breech, a longitudinally movable breeching structure, and firing means, of means to adapt the gun for the firing of the cartridges one by one by hand consisting of a rigid cartridge-supporting member removably arranged in said opening and having a cartridge-supporting seat to form the rigid bottom of the space immediately back of the breech in the rearward position of the breeching structure, said part also having a cartridge-introducing and shell-ejecting opening entering the same immediately back of the breech.

In testimony whereof I affix my signature.

CHARLES A. NELSON.
